UNITED STATES PATENT OFFICE.

CHARLES F. SMITH, OF NEW BRITAIN, CONNECTICUT, ASSIGNOR TO THE LANDERS, FRARY & CLARK, OF SAME PLACE.

DESIGN FOR A KNIFE-HANDLE, &c.

SPECIFICATION forming part of Design No. 25,562, dated June 2, 1896.

Application filed April 27, 1896. Serial No. 589,324. Term of patent 7 years.

To all whom it may concern:

Be it known that I, CHARLES F. SMITH, a citizen of the United States, residing at New Britain, in the county of Hartford and State of Connecticut, have invented and produced a new and original Design for Cutlery-Handles, of which the following is a specification, reference being had to the accompanying drawings, in which—

10 Figure 1 is a side elevation of a knife-handle, showing my design. Fig. 2 is an edge view of the same.

My handle comprises a tang 3 of a knife or fork, the bolster 4, tip 5, and scales 6.

15 In the middle portion of the scales is an inlaid ornament having a central circular hub 7, longitudinal arms 8 8, projecting from said

hub in opposite directions and in alinement with each other, and cross-arms 9 9, standing transversely to the arms 8 8, but otherwise 20 having the same relations to each other and the hub 7. While this cross-like ornament as a whole shows only when the handle is seen in side view, it may be observed that portions of the transverse arms 9 9 show in plan or edge 25 view, as in Fig. 2.

What I claim is—

The design for a cutlery-handle substantially as herein shown and described.

CHARLES F. SMITH.
